(57) **ABSTRACT**

The invention relates to a method for the synthesis of galanthamine, the derivatives and analogues thereof of formula (1) where R_1 =a hydrogen atom, R_2 =a hydroxy group, R_1 and R_2 together form $=O$, R_3 , R_4 , and R_5 independently=a hydrogen atom, a hydroxy group or a (C_1-C_2) alkoxy group, $R_6=H$, (C_1-C_{12}) alkyl, $(CH_2)_nNR_7R_8$, or $-(CH_2)_nN^+R_7R_8R_9$ where $n=1$ to 12, $Z=$ two hydrogen atoms, or an oxygen atom and $X=$ an oxygen, sulphur or nitrogen atom, or a $-SO$, $-SO_2$, or $-NR_6$ group where R_6 is as defined above or is an amine protecting group.

1

TOTAL SYNTHESIS OF GALANTHAMINE,
ANALOGUES AND DERIVATIVES THEREOF

Matter enclosed in heavy brackets [ ] appears in the original patent but forms no part of this reissue specification; matter printed in italics indicates the additions made by reissue.

The present patent application is a non-provisional application of International Application No. PCT/FR02/02045, filed Jun. 14, 2002.

The present invention relates to a method of synthesizing galanthamine, its analogues, and its derivatives, and to the corresponding synthesis intermediates.

(-)-Galanthamine of formula (A)

is an alkaloid which is isolated from the family of the Amaryllidaceae and acts as a competitive, selective, and reversible inhibitor of acetylcholinesterase (Harvey A. L. (1995), *Pharmac. Ther.*, 68, 113).

It has been used for a number of years in the treatment of myasthenia and in certain neurological diseases such as poliomyelitis, as an anticholinesterase agent, and as a parasympathomimetic agent.

In particular this compound enhances the cognitive functions of persons suffering from Alzheimer's disease, which is characterized by damage to the cholinergic neurotransmission (Weinstock M. (1999), *CNS Drugs*, 12, 307). At present galanthamine is sold for this indication in Austria and Sweden and should shortly be so sold in the other countries of Europe and in the United States.

(-)-Galanthamine may be extracted from a variety of plant sources, in particular from *Galanthus nivalis*, *G. narcissus*, *G. leucojum* or *G. crinum*, but in very small quantities, which are inadequate for commercial use.

Galanthamine was first synthesized by Barton D. H. R. et al. (*J. Chem. Soc.* (1962), 806), the key step of this method being the oxidative cyclization of the phenol, of which the yield is only 0.5%. Many groups have attempted to improve the yields of this synthesis method so as to allow it to be used on the industrial scale; thus Czollner L. et al. (*Tetrahedron Letters* (1998), 39, 2087) obtained a yield of 45 to 50% and Krikorian et al. (*Synthetic Communications* (2000), 30 (16), 2833) yields of 60%. However, despite the increase in these yields, these methods remain difficult to implement on the industrial scale.

Furthermore, a number of groups have attempted to develop syntheses of galanthamine, its analogues and derivatives by nonbiomimetic routes.

Thus the group of Ishisaki M. et al. (*J. Org. Chem.* (1993), 58, 3877) describes a synthesis by free-radical reaction of lycoramine, an alkaloid from the galanthamine family. Following a retrosynthetic analysis of lycoramine (1,2-dihydrogalanthamine), the authors show that the compound of structure (B)

2

(B)

5
10

is able to lead only to the total synthesis of lycoramine, in 3 steps with an overall yield of 13%.

This intermediate therefore does not make it possible to obtain galanthamine.

Galanthamine and its derivatives such as lycoramine are characterized by the presence of a spiro quaternary carbon, the creation of which has been found to be the limiting step in the total synthesis.

The inventors were the first to describe a new strategy to form this critical quaternary carbon in lycoramine (Gras E. et al., *Tetrahedron Letters* (1999), 40, 9243), using an intramolecular Heck reaction; they synthesized the intermediate of formula (C)

(C)

30
35

and used it to prepare lycoramine by introduction of an amine group, Pictet-Spengler cyclization, and reduction with LiAlH_4 in tetrahydrofuran in accordance with the technique described by Ishisaki M. (reference already cited).

More recently Trost B. M. et al. (*J. Am. Chem. Soc.* (2000), 122 (45), 11262) have described the first full enantioselective synthesis of (-)-galanthamine without using the oxidative coupling of the phenol: they perform a cyclization by an intramolecular Heck reaction in the presence of a bidentate alkylphosphine ligand and a palladium catalyst.

This synthesis, however, is made up of 15 steps and its overall yield is 1%.

Pilger C. et al. (*Synlett* (2000), 8, 1163) and Parsons P. J. et al. (*Tetrahedron Letters* (2001), 42, 2209) have likewise described new synthetic pathways for the skeleton of 3-deoxygalanthamine, using a selective intramolecular Heck reaction as the key step. This approach does not allow creation of the allyl function, which is essential for the biological activity.

In view of the importance of the market for galanthamine, its derivatives, and its analogues, it is absolutely indispensable to develop a synthesis which is easy, rapid, and economically viable.

The inventors have now found, surprisingly, that by using an oxidizing agent mixed with a support, and starting from the compound of formula (C) or an analogue, they obtained galanthamine or its derivatives in conditions which are compatible with an industrial utilization.

3

The invention accordingly provides a method of synthesizing compounds of formula (1)

(1)

4

is oxidized to a spirodienone of formula (11),

(11)

in which

either R₁ represents a hydrogen atom and R₂ represents a hydroxyl group, or R₁ and R₂ together form =O,

R₃, R₄ and R₅ represent each independently of one another a hydrogen atom, a hydroxyl group or a (C₁–C₁₂)alkoxy group,

R₆ represents a hydrogen atom, a (C₁–C₁₂)alkyl group, a group —(CH₂)_nNR₇R₈ or a group —(CH₂)_nN⁺R₇R₈R₉ where n=1 to 12, R₇ and R₈ represent each independently of one another a hydrogen atom; a cyano; (C₁–C₄)alkyl; aryl (C₁–C₄)alkyl; aryl(C₁–C₄)alkenyl; (C₁–C₄)alkyl-carbonyl or arylcarbonyl radical; the alkyl, alkenyl, and aryl radicals being optionally substituted by one or more identical or different radicals selected from halo, hydroxyl, alkoxy, alkylthio, acyl, free, salt-form or esterified carboxyl, cyano, nitro, mercapto or amino radicals, the amino radical being itself optionally substituted by one or more identical or different alkyl radicals; or R₇ and R₈ are linked to each other and form, together with the nitrogen atom to which they are attached, a heterocycle; and R₉ represents a hydrogen atom or a cyano, (C₁–C₄)alkyl, aryl(C₁–C₄)alkyl, aryl(C₁–C₄)alkenyl, alkylcarbonyl or arylcarbonyl radical, the alkyl, alkenyl, and aryl radicals being optionally substituted by one or more identical or different radicals selected from halo, hydroxyl, alkoxy, alkylthio, acyl, free, salt-form or esterified carboxyl, cyano, nitro, mercapto or amino radicals, the amino radical being itself optionally substituted by one or more identical or different alkyl radicals;

Z represents either two hydrogen atoms or one oxygen atom, and

X represents alternatively an oxygen atom or a sulfur atom or a nitrogen atom or an —SO group or an —SO₂ group or a group —NR₆ where R₆ is as defined above or represents an amine-protective group,

characterized in that it comprises a step in which an α,β-ethylenic ketone of formula (10)

(10)

60

65

(7)

15

In one advantageous embodiment of the method the support is a mixture of silica and alumina.

In one particularly advantageous embodiment the mixture of silica and alumina is a 50/50 mixture.

In one preferred embodiment the oxidation is performed in the presence of benzeneselinic anhydride mixed with a support, preferably an inorganic support. By way of example mention may be made in particular of molecular sieves whose size is preferably between 3 and 5 Å, and silica/alumina mixtures.

The compounds of formula (1) are analogues and derivatives of galanthamine, particularly basic analogues of galanthamine in which the nitrogen atom of the ring D can be converted to its salt form, and analogues containing an iminium function in the ring D, such as those described in international application WO 97/03987 and in the article by Mary A. et al. (Bioorganic and Medicinal Chemistry (1988), 6, 1835). These compounds possess 3 asymmetric carbons and may therefore exist in the form of pure stereoisomers or mixtures. Preferably the 3 carbon is of α configuration as in natural galanthamine.

In one advantageous embodiment of the method according to the invention a derivative of formula (6)

(6)

in which Hal represents a halogen atom selected from bromine and iodine atoms, R₃, R₄, and R₅ are as defined in claim 1, and R₁₀ represents an amine group or a hydroxyl group is reacted with (1,4-dioxaspiro[4.5]dec-7-en-8-yl)acetic acid of formula (7),

5

and a compound of formula (8)

is obtained which is cyclized by an intramolecular Heck reaction to give a compound of formula (9)

the cyclization reaction is performed under conventional conditions known to the skilled worker, particularly in the presence of a palladium catalyst or a palladium(0) precursor catalyst, such as for example tris(dibenzylideneacetone) dipalladium, and bidentate alkylphosphine derivatives such as for example 1,2-bis(diphenylphosphino)ethane (dppe) or 1,2-bis(dicyclohexylphosphino)ethane (depe), and in a mixture of thallium acetate and acetonitrile or dimethylacetamide; subsequently the dioxolane function of the compound of formula (9) is deprotected, in the presence for example of a hydride acceptor such as, for example, triphenylcarbenium tetrafluoroborate or triphenylcarbenium hexafluorophosphate, to give the α,β -ethylenic ketone of formula (10)

which is oxidized in the presence of benzeneseleninic anhydride, to which a mixture, preferably 50/50, of silica and alumina has been added, to give a compound of formula (11)

in which R₃, R₄, and R₅ and X are as defined above; subsequently the amine group is introduced into said compound of formula (11) by opening the lactone with an amine of for-

6

mula NH₂R₆ where R₆ is as defined above; this reaction is accompanied by a spontaneous, Michael-type addition reaction of the intermediately generated phenol with the dienone to form, with a quantitative yield, the corresponding amide of formula (12)

in which R₃, R₄, R₅ and X are as defined above.

Subsequently, the amide of formula (12) is cyclized, for example by a Pictet-Spengler-type reaction; said reaction may be performed in the presence of paraformaldehyde and trifluoroacetic acid; this gives a compound of formula (1a)_a

whose diastereoselective reduction, for example with L-Selectride®, leads to the corresponding derivative of formula (1b)

which is itself reduced under conventional conditions to give the final, corresponding compound of formula (1c)

According to another embodiment of the invention, when it is desired to obtain optically active compounds of formula (1a) to (1c), the compound (12) or (1a) is subjected to resolution under conventional conditions known to the skilled worker, and the steps described above are conducted.

In one particularly advantageous embodiment of the invention the method allows galanthamine to be obtained in the form of the racemate or of its optically pure isomers.

The method according to the invention allows galanthamine, its analogues, and its derivatives to be obtained within a reasonable number of steps which are compatible with an industrial process.

The invention likewise provides compounds of formula 5 (11) and (12)

(11)

(12)

in which R₃, R₄, R₅, R₆, and X are as defined above, which are useful as synthesis intermediates.

The invention further provides compounds of formula (8) and (9)

(8)

(9)

in which Hal, R₃, R₄, and R₅ are as defined above and X represents a sulfur atom, a nitrogen atom, an —SO group, an —SO₂ group, a group —NR₆ where R₆ is as defined above or represents an amine-protective group.

The examples which follow illustrate the invention, though without limiting it.

EXAMPLE 1

Total Synthesis of Galanthamine

1.1 2-iodo-6-methoxyphenyl (1',4'-dioxaspiro[4.5]dec-7'-en-8'-yl)acetate (8)

500 mg (2.52 mmol; 1.05 eq) of (1,4-dioxaspiro[4.5]dec-7-en-8-yl)acetic acid (7) in solution in 10 ml of CH₂Cl₂ at 0° C. are admixed gradually with 970 mg (5.05 mmol; 2.10 eq) of EDC in solution in 30 ml of CH₂Cl₂, then with 308 mg (2.52 mmol; 1.05 eq) of demethylaminopyridine in solution in 10 ml of CH₂Cl₂. The reaction mixture is stirred at 0° C. for 15 minutes and then 600 mg (2.4 mmol; 1.00 eq) of 2-iodo-6-methoxyphenol 6 in solution in 10 ml of CH₂Cl₂ are added. After 5 hours of stirring at ambient temperature the reaction mixture is hydrolyzed and extracted with ethyl acetate (AcOEt). The organic phase is washed with saturated aqueous sodium chloride solution, dried over magnesium sulfate and evaporated under vacuum. The residue is purified by flash chromatography on silica gel (elution: heptane/AcOEt: 7/3) to give 825 mg (80%) of 2-iodo-6-methoxyphenyl (1',4'-dioxaspiro[4.5]dec-7'-en-8'-yl)acetate 8 in the form of a colorless oil.

Elemental analysis: calculated for C₁₇H₁₉IO₅: C, 47.46; H, 4.45; O, 18.59; found: C, 47.34; H, 4.45; O, 18.41.

10 1.4 8-methoxy-3,4,4a,8a-tetrahydro-spiro-chromen-2-one-[4,4']-cyclohex-2',5'-dien-1'-one (11)

125 mg (0.48 mmol; 1.0 eq) of 8-methoxy-3,4,4a,8a-tetrahydro-spiro-chromen-2-one-[4,4']-cyclohex-2'-en-1'-one (10) in solution in 12 ml of anhydrous chlorobenzene containing 400 mg of silica and 400 mg of alumina are admixed with 691 mg (1.92 mmol; 4.0 eq) of benzeneselinic anhydride. After 24 hours of stirring at reflux the reaction mixture is filtered on a frit, rinsed with MeOH and evaporated under reduced pressure. The residue is taken up in CH_2Cl_2 and then washed with saturated aqueous sodium chloride solution. The organic phase is dried over magnesium sulfate and evaporated under vacuum. Purification by flash chromatography on silica gel (elution: heptane then heptane/AcOEt: 5/5) of the residue obtained gives 62 mg (50%) of 8-methoxy-3,4,4a,8a-tetrahydro-spiro-chromen-2-one-[4,4']-cyclohex-2',5'-dien-1'-one (11), isolated in the form of a yellow powder.

EXAMPLE 2

Total Synthesis of Azagalanthamine

2.1 2-(1,4-dioxaspiro[4.5]dec-7-en-8-yl)-N-(2'-iodo-6'-methoxyphenyl)acetamide (16)

A solution of (1,4-dioxaspiro[4.5]dec-7-en-8-yl) acetic acid (567 mg; 2.86 mmol; 1 eq) (7) and 2-iodo-6-methoxyaniline (1 g; 2.86 mmol; 1 eq) in anhydrous dichloromethane (30 mL) is admixed with 2-chloro-1-methylpyridinium iodide (1.46 g; 5.73 mmol; 2 eq) and

14

triethylamine (3.98 mL; 28.65 mmol; 10 eq). The reaction mixture is heated at reflux for 20 hours. After cooling and acidification with 1N HCl solution to pH=5–6, the mixture is extracted with dichloromethane. The organic phases are washed with saturated aqueous sodium chloride solution, dried over magnesium sulfate and evaporated under vacuum. Purification by flash chromatography on silica gel (eluent: heptane/ethyl acetate 4/6) gives 1.10 g of 2-(1,4-dioxaspiro[4.5]dec-7-en-8-yl)-N-(2'-iodo-6'-methoxy-phenyl)acetamide (16) in the form of a yellow foam (yield: 90%).

Elemental analysis calculated for C₁₇H₂₀INO₄ (m.p.: 429.25) C: 47.57; H: 4.70; N: 3.26; O: 14.91; found C: 47.39; H: 4.59; N: 3.01; O: 15.16.

IR (CHCl₃) ν (cm⁻¹): 3382 (N—H); 1687 (C=O)

MS (ES) m/z: 429.8 [M⁺H]⁺.

¹H NMR (CDCl₃, 300 MHz) δ (ppm): 7.43 (dd, J=8.0, J=1.2; 1H; H3'); 7.18 (broad s; 1H; NH); 6.98 (t, J=8.0; 1H; H4'); 6.91 (dd, J=8.0, J=1.2; 1H; H5'); 5.72 (broad s, 1H; H4); 3.99 (s; 4H; Hdioxolane); 3.80 (s; 3H; OCH₃); 3.15 (s; 2H; H2); 2.45 (broad s; 1H; H8); 2.37 (broad s, 1H; H5); 2.37 (broad s, 2H; H6); 1.85 (t, J=6.4; 2H; H7).

¹³C NMR (CDCl₃, 62.9 MHz) δ (ppm): 169.2 (C(O)NH); 155.5 (C6'); 132.9 (C1'); 130.8 (C3'); 129.6 (C4'); 128.1 (C8); 124.9 (C7); 111.7 (C5'); 107.7 (C5); 99.8 (C2'); 64.8 (Cdioxolane); 56.1 (OCH₃); 45.7 (C2); 35.9 (C6); 38.2 (C4); 35.0 (C3).

2.2 2-(1,4-dioxaspiro[4.5]dec-7-en-8-yl)-N-(2'-iodo-6'-methoxyphenyl)-N-methylacetamide (17)

A solution of 2-(1,4-dioxaspiro[4.5]dec-7-en-8-yl)-N-(2'-iodo-6'-methoxyphenyl)acetamide (16) (1.88 g; 4.39 mmol; 1 eq) in 150 mL of anhydrous tetrahydrofuran (THF) is admixed dropwise at 0°C. with a suspension of NaH (263 mg; 10.98 mmol; 2.5 eq) in anhydrous THF (120 mL). After 15 minutes the reaction mixture is allowed to return to ambient temperature and dimethyl sulfate (1.04 mL; 0.2 mmol; 2.5 eq) is added. The reaction mixture is kept with stirring at ambient temperature for 2 hours and then the reaction is stopped by adding saturated aqueous sodium hydrogencarbonate solution. Following extraction with ether, the organic phases are washed with saturated aqueous sodium chloride solution, dried over magnesium sulfate and evaporated under vacuum. Purification by flash chromatography on silica gel (eluent: heptane/ethyl acetate 4/6) of the residue obtained allows 26.9 mg of the product 2-(1,4-dioxaspiro[4.5]dec-7-en-8-yl)-N-(2'-iodo-6'-methoxyphenyl)-N-methylacetamide (17) to be obtained in the form of a colorless oil (yield: 86%). The ¹H NMR spectrum reveals that the product is a mixture of two rotamers in approximately 1:4 proportion.

Elemental analysis calculated for C₁₈H₂₂INO₄ (m.p.: 443.28) C: 48.77; H: 5.00; found: C 48.98; H: 4.88.

30 2.5 8-methoxy-1-methyl-3,4-dihydro-1H-quinolin-2-one-[4,4']-cyclohex-2',5'-dien-1'-one (20)

35 120 mg (0.44 mmol; 1.0 eq) of 8-methoxy-1-methyl-3,4-dihydro-1H-quinolin-2-one-[4,4']-cyclohex-5'-ene-1'-one 19 in solution in 10 mL of chlorobenzene containing 400 mg of alumina and 400 mg of silica are admixed with 637 mg (1.77 mmol; 4.0 eq) of benzeneselinc anhydride. After 24 hours of stirring at reflux the reaction mixture is filtered on a frit, washed with MeOH and evaporated under reduced pressure.

The residue is taken up in and extracted with CH_2Cl_2 , the aqueous phase being saturated with sodium chloride. The organic phase is washed with saturated aqueous sodium chloride solution, dried over magnesium sulfate and evaporated under vacuum. Purification by flash chromatography on silica gel (elution: heptane/ethyl acetate: 3.5/6.5) of the residue obtained gives 73 mg of 8-methoxy-1-methyl-3,4-dihydro-1H-quinolin-2-one-[4.4']-cyclohex-2',5'-dien-1'-one (20), isolated in the form of a yellow foam (yield: 61%).

2.6 ($\pm$)-11-oxazanarweddine(21)

This compound is prepared from 8-methoxy-1-methyl-3,4-dihydro-1H-quinolin-2-one-[4.4']-cyclohex-2',5'-dien-1'-one (20) in accordance with the procedure described in steps 1.5 and 1.6 of example 1.

2.7 ($\pm$)azagalanthamine (22)

This compound is obtained from (21) in accordance with the procedure described in steps 1.7 and 1.8 of example 1.

The invention claimed is:

1. A method of synthesizing compounds of formula (1)

in which

either R₁ represents a hydrogen atom and R₂ represents a hydroxyl group, or R₁ and R₂ together form =O,

R₃, R₄ and R₅ represent each independently of one another a hydrogen atom, a hydroxyl group or a (C₁—C₁₂)alkoxy group,

R₆ represents a hydrogen atom, a (C₁—C₁₂)alkyl group, a group $-(\text{CH}_2)_n\text{NR}_7\text{R}_8$ or a group $-(\text{CH}_2)_n\text{N}^+\text{R}_7\text{R}_8\text{R}_9$ where n=1 to 12, R₇ and R₈ represent each independently of one another a hydrogen atom; a cyano; (C₁—C₄)alkyl; aryl(C₁—C₄)alkyl; aryl(C₁—C₄)alkenyl; (C₁—C₄)alkyl-carbonyl or arylcarbonyl radical; the alkyl, alkenyl, and aryl radicals being optionally substituted by one or more identical or different radicals selected from halo, hydroxyl, alkoxy, alkylthio, acyl, free, salt-form or esterified carboxyl, cyano, nitro, mercapto or amino radicals, the amino radical being itself optionally substituted by one or more identical or different alkyl radicals; and R₉ represents a hydrogen atom or a cyano, (C₁—C₄)alkyl, aryl(C₁—C₄)alkyl, aryl

50 (C₁—C₄)alkenyl, alkylcarbonyl or arylcarbonyl radical, the alkyl, alkenyl, and aryl radicals being optionally substituted by one or more identical or different radicals selected from halo, hydroxyl, alkoxy, alkylthio, acyl, free, salt-form or esterified carboxyl, cyano, nitro, mercapto or amino radicals, the amino radical being itself optionally substituted by one or more identical or different alkyl radicals;

55 R represents either two hydrogen atoms or one oxygen atom, and

5

X represents alternatively an oxygen atom or a sulfur atom on an —SO group or an —SO₂ group or a group —NR₆ where R₆ is as defined above or represents an amine-protective group,

comprising providing an α,β -ethylenic ketone of formula (10)

(10)

30 and oxidizing said ketone to a spirodienone of formula (11)

45 wherein said spirodienone of formula (11) is thereafter transformed to produce a compound of formula (1).

2. A method according to claim 1, characterized in that the oxidation is performed in the presence of benzeneselininic anhydride and a support.

3. A method according to claim 2, characterized in that the support is selected from the group consisting of molecular sieves and mixtures of silica and alumina.

4. A method according to claim 3, characterized in that the mixture of silica and alumina is a 50/50 mixture.

5. A method according to claim 1, characterized in that a compound of formula (6)

(6)

60 in which Hal represents a halogen atom selected from bromine and iodine atoms, R₃, R₄, and R₅ are as defined in claim 1, and R₁₀ represents an amine group or a hydroxyl

19

group is reacted with (1,4-dioxaspiro[4.5]dec-7-en-8-yl) acetic acid of formula (7),

20

which is oxidized in the presence of benzeneseleninic anhydride, to which a mixture of silica and alumina has been added, to give a compound of formula (11)

and a compound of formula (8)

is obtained which is cyclized by an intramolecular Heck reaction to give a compound of formula (9)

(9) 35

which is cyclized to give a compound of formula (1a),

in the presence of a palladium or a palladium(0) precursor catalyst and of bidentate alkylphosphine ligands in a solvent, then the dioxolane function of the compound of formula (9) is deprotected to give the α,β -ethylenic ketone of formula (10)

(10) 55

which is optionally subjected to a diastereoselective reduction to give the corresponding derivative of formula (1b),

(1b)

21

whose amide function can optionally be reduced to give a compound of formula (1c)

6. A method according to claim 5, characterized in that the compound of formula (12) is resolved and then the synthesis is continued to give the compounds of formula (1a) to (1c) in their optically active forms.

7. A method according to claim 5, characterized in that the compound of formula (1a) is resolved and then the synthesis is continued to give the compounds of formula (1b) to (1c) in their optically active forms.

8. A method according to claim 1, characterized in that galanthamine is prepared in the form of the racemate or of its optically pure isomers.

9. Compound of formula (11)

in which R₃, R₄ and R₅ represent each independently of one another a hydrogen atom, a hydroxyl group or a (C₁–C₁₂)alkoxy group and X represents alternatively an oxygen atom or a sulfur atom or an —SO group or an —SO₂ group or a group —NR₆ where R₆ represents a hydrogen atom, a (C₁–C₁₂)alkyl group, a group —(CH₂)_nNR₇R₈ or a group —(CH₂)_nN⁺R₇R₈R₉ where n=1 to 12, R₇ and R₈ represent each independently of one another a hydrogen atom; a cyano; (C₁–C₄)alkyl; aryl (C₁–C₄)alkyl; aryl(C₁–C₄)alkenyl; (C₁–C₄)alkyl-carbonyl or arylcarbonyl radical; the alkyl, alkenyl, and aryl radicals being optionally substituted by one or more identical or different radicals selected from halo, hydroxyl, alkoxy, alkylthio, acyl, free, salt-form or esterified carboxyl, cyano, nitro, mercapto or amino radicals, the amino radical being itself optionally substituted by one or more identical or different alkyl radicals; or represents an amine-protective group.

10. Compounds according to claim 9, characterized in that R₃=OCH₃, R₄=R₅=H and X=O, NH or N—CH₃.

22

11. Compound of formula (8)

15 in which Hal represents a halogen atom selected from bromine and iodine atoms, and R₃, R₄, and R₅ represent each independently of one another a hydrogen atom, a hydroxyl group or a (C₁–C₁₂)alkoxy group; and X represents alternatively an oxygen atom or a sulfur atom or a nitrogen atom or an —SO group, an —SO₂ group or a group —NR₆ where R₆ represents a hydrogen atom, a (C₁–C₁₂)alkyl group, a group —(CH₂)_nNR₇R₈ or a group —(CH₂)_nN⁺R₇R₈R₉ where n=1 to 12, R₇ and R₈ represent each independently of one another a hydrogen atom; a cyano; (C₁–C₄)alkyl; aryl (C₁–C₄)alkyl; aryl(C₁–C₄)alkenyl; (C₁–C₄)alkyl-carbonyl or arylcarbonyl radical; the alkyl, alkenyl, and aryl radicals being optionally substituted by one or more identical or different radicals selected from halo, hydroxyl, alkoxy, alkylthio, acyl, free, salt-form or esterified carboxyl, cyano, nitro, mercapto or amino radicals, the amino radical being itself optionally substituted by one or more identical or different alkyl radicals; or represents an amine-protective group.

20 35 12. Compounds according to claim 11, characterized in that Hal=I, R₃=OCH₃, R₄=R₅=H and X=NH or N—CH₃.

13. Compound of formula (12)

40 45 50 55 60 65 70 75 80 85 90 95 in which R₃, R₄ and R₅ represent each independently of one another a hydrogen atom, a hydroxyl group or a (C₁–C₁₂)alkoxy group; and R₆ represents a hydrogen atom, a (C₁–C₁₂)alkyl group, a group —(CH₂)_nNR₇R₈ or a group —(CH₂)_nN⁺R₇R₈R₉ where n=1 to 12, R₇ and R₈ represent each independently of one another a hydrogen atom; a cyano; (C₁–C₄)alkyl; aryl (C₁–C₄)alkyl; aryl(C₁–C₄)alkenyl; (C₁–C₄)alkyl-carbonyl or arylcarbonyl radical; the alkyl, alkenyl, and aryl radicals being optionally substituted by one or more identical or different radicals selected from halo, hydroxyl, alkoxy, alkylthio, acyl, free, salt-form or esterified carboxyl, cyano, nitro, mercapto or amino radicals, the amino radical being itself optionally substituted by one or more identical or different alkyl radicals; and X represents alternatively an oxygen atom or a sulfur atom or an —SO group or an —SO₂ group or a group —NR₆ where R₆ is as defined above or represents an amine-protective group.

23

14. Compound of formula (9)

(9)

5

10

15

in which Hal, R₃, R₄, and R₅ are as defined in claim 1 and X represents alternatively *an oxygen atom or* sulfur atom or a nitrogen atom or an —SO group, an —SO₂ group or a group —NR₆ where R₆ represents a hydrogen atom, a (C₁—C₁₂) alkyl group, a group —(CH₂)_nNR₇R₈ or a group —(CH₂)_nNR₇R₈R₉ where n=1 to 12, R₇ and R₈ represent each independently of one another a hydrogen atom; a cyano; (C₁—C₄) alkyl; aryl(C₁—C₄)alkyl; aryl(C₁—C₄)alkenyl; (C₁—C₄)alkyl-carbonyl or arylcarbonyl radical; the alkyl, alkenyl, and aryl radicals being optionally substituted by one or more identical or different radicals selected from halo, hydroxyl, alkoxy, alkylthio, acyl, free, salt-form or esterified carboxyl, cyano, nitro, mercapto or amino radicals, the amino radical being itself optionally substituted by one or more identical or different alkyl radicals; or represents an amine-protective group.

15. The process of claim 2 wherein said support is an inorganic support.

24

16. A compound according to claim 11 as follows:

17. A compound according to claim 14 as follows:

* * * *
